ELECTRIC WEFT DETECTOR FOR LOOMS

Richard G. Turner, Worcester, Mass., assignor to
Crompton & Knowles Loom Works, Worcester,
Mass., a corporation of Massachusetts

Application September 23, 1944, Serial No. 555,447

17 Claims. (Cl. 139—273)

This invention relates to improvements in electrical weft detectors for looms and it is the general object of the invention to provide a weft detector with a sideslipping detector finger movable angularly at the time of indication of weft exhaustion to close an electric contact.

It is a further object of my present invention to provide a weft detector with a detecting unit slideable within a casing or housing and including an arm or the like extending laterally from the detector finger for engagement with the electric contact.

It is another object of my present invention to hold the detector finger rearwardly by a spring or the like which engages the aforesaid lateral arm and forces the latter against a fixed part of the weft detector for the purpose of restoring the finger to normal position after a detecting operation.

It is still another object of my present invention to provide a detector having a casing made of upper and lower parts one of which is made of electric insulating material and is provided with a lug or enlargement which carries the aforesaid electric contact and also provides a flat surface against which the lateral arm is normally held by the previously mentioned spring. One wall of the casing forming members is notched to receive the lug for the purpose of assisting in holding the two parts of the detector casing in proper working position.

It is a further object of my present invention to provide an electric weft detector of such construction that the detector finger when indicating weft exhaustion moves through a primary stage around one pivot to establish contact with an electrical part, such as a binding post or contact, and thereafter moves about the contact as a center during the secondary stage of indication.

With these and other objects in view which will appear as the description proceeds, my invention resides in the combination and arrangement of parts hereinafter described and set forth.

In the accompanying drawings wherein a convenient embodiment of my invention is set forth,

Fig. 1 is a front elevation of a portion of a weft replenishing loom having my improved weft detector applied thereto.

Fig. 2 is a horizontal enlarged section on line 2—2 of Fig. 1.

Fig. 3 is a vertical section on line 3—3 of Fig. 2.

Fig. 4 is a plan view of the detector with the upper part of the casing removed, and showing the detector moved forwardly by an ample supply of weft on the bobbin being detected.

Fig. 5 is a view similar to Fig. 4 but indicating the movement of the detector finger during the first stage of the detecting operation when indicating weft exhaustion.

Fig. 6 is a view similar to Fig. 5 but showing completion of the second stage of movement of the detector finger when indicating weft exhaustion.

Fig. 7 is a vertical section on line 7—7 of Fig. 2, and

Fig. 8 is a rear elevation looking in the direction of arrow 8, Fig. 2.

Referring to Fig. 1, I have shown a loom frame 10 having fixed thereto a stand 11 which supports a bobbin magazine M provided with reserve bobbins W. The loom is provided with a lay 12 having a shuttle box 13 the front wall 14 of which is formed with a horizontal feeler slot 15. The stand 11 supports a relatively large stud 16 on which is mounted a block or the like 17 in the lower part of which a carrier 18 is mounted for sliding movement toward and from the shuttle box. Secured to the front of the carrier is a detector support 19 which extends to the right from the carrier 18 to a position in front of the slot 15. The carrier and support 19 are normally stationary but can be moved forwardly by mechanism not shown at the time of transfer. The matter thus far described of itself forms no part of my present invention but is set forth to indicate one manner of use of the invention to be set forth hereinafter.

The detector D forming the subject matter of my invention is formed of top and bottom shells or members 25 and 26, respectively, the upper shell having integral therewith a laterally extending foot 27 slotted as at 28 to receive a bolt 29 which passes through the support 19. A nut 30 on the upper end of the bolt 29 serves to hold the shell 25 in rigid position with respect to the support 19, but permits adjustment of the shell in the direction of the length of the lay and also permits angular adjustment relatively to the support.

The upper shell or member 25 is provided with a flat thin horizontal web 35 which lies along the under surface of the support 19 and is provided on the under side thereof with spaced depending ribs 36 which extend in a direction toward and from the slot 15. A depending tubular bearing 37 integral with web 35 receives a screw 38 the head 39 of which is flush with the top of shell 25 and bottom of support 19. A peripheral wall 40 depends from the web 35 and is formed with a depending tongue 41. The shell or mem-

ber 25 is perfectly metallic so that an electrical current can pass therefrom to support 19 which is electrically grounded to the frame of the loom.

The bottom shell or member 26 is formed with a thin horizontal web 45 similar to web 35 and provided with spaced upwardly extending ribs 46 similar to the rib 36. An upright tubular bearing 47 is integral with the web 45 and engages the depending bearing 37 and also has threaded thereinto the lower end of screw 38. The web 45 has extending upwardly therefrom a peripheral wall 48 abutting wall 40. The left hand portion of wall 48 is provided with a notch 49 which receives the aforesaid tongue 41. The latter fits into the notch 49 and cooperates with the screw 39 to prevent angular movement of the two shells or members 25 and 26. The bottom shell 26 is preferably made of an electric insulating material, such as a plastic, although this is not essential so far as certain features of the invention are concerned.

The rear part of the peripheral wall 48 is provided with an enlarged integral lug 50 which projects behind the rear part of shell 25 and above the top of wall 48, see Fig. 7. Lug 50 fits between and engages the opposite ends 51 and 52 of the depending wall 40 on the upper shell 25, see Fig. 8. Engagement of the lug 50 with the wall ends 51 and 52 serves further to hold the two parts of the shell in fixed angular position with respect to each other.

It is thus seen that the two shells have their walls in engagement with each other and that the screw 38 holds the shells together as indicated in Figs. 3 and 7 and further that the tongue 41 and the lug 50 cooperate with those parts of the walls which they engage to hold the two shells in correct angular position. The webs 35 and 45 are vertically spaced and together with the side walls define an interior compartment designated generally at C in which is located certain parts of the detecting mechanism.

As indicated in Figs. 3 and 4 a backwardly and forwardly extending rod 60 is spaced intermediate the webs 35 and 45 and enters the lug 50 as at 61. The forward part of rod 60 is held in two aligned notches, one of them indicated at 62 being in the top wall 40 and the other indicated at 63 being in the bottom wall 48. When the two shells are held together as already described the rod is held in fixed position with respect to them.

The detector element designated generally at 65 comprises a wire 66 to the rear end of which is secured a detector tip 67. The forward end of wire 66 is secured to a sliding carrier 68 which may preferably be formed of sheet metal of such a height as to fit loosely between the ribs 36 and 46. The carrier 68 is provided with a lateral arm 69 which engages the rear vertical flat surface 70 of the lug 50 under normal conditions. The wire 66 is secured to this arm and the carrier has a forwardly extending part 71 terminating in a laterally bent end 72 extending between certain of the ribs 36 and 46.

A flat spring 75 is located between the top and bottom shells 25 and 26 and is of general U-shaped form as shown for instance in Figs. 4 to 6. This spring is located between and slides along the left hand ribs 36 and 46 as seen in Fig. 6. The rear end of rod 60 passes through the rear end 76 of the spring 75, while the forward end of the rod 60 passes through the front end 77 of the spring. The rod therefore positions the ends of the spring. The rod 60 also passes through a hole 78, see Fig. 4, in the lateral arm 69 against

which the rear end 76 of the spring presses due to its own resilience.

The lug 50 has threaded thereinto a contact screw or binding post 80 held in position by a lock nut 81 which is behind and out of contact with the top shell 25. A cap screw 82 holds a wire 83 against the nut 81 to establish electrical connection with the screw. The wire 83 extends to any convenient form of loom controlling electric circuit not shown which of itself forms no part of my present invention. It is thought sufficient to state that when arm 69 engages screw 80 an electrical contact will be closed the effect of which will be to close a loom controlling circuit.

The shell 26 has been described hereinbefore as made of electric insulating material, but I have also made it of metal and fastened the lug 50 to it so that the screw 80 is insulated from the shell 26.

Under normal conditions the detector finger 65, lateral arm 69, and flat spring 75 are in the relative position shown in full lines in Fig. 5 with the arm 69 held yieldingly against the forward vertical surface 70 of the lug or block 50. Under these conditions arm 69 is out of contact with screw 80. If an ample supply of weft is present on bobbin B during the detecting operation the teeth on the detector tip will be held against lateral slipping with respect to the bobbin and the parts will slide forwardly to the position shown in Fig. 4 with little or no angular movement on the part of the detector finger 65. During this movement the arm 69 is guided between the ribs 35 of the top and bottom shells and the forward lateral extension 72 engages the upper adjacent rib 36 to hold the detector in its proper detecting position against the action of gravity. The rod 60 also serves to guide the detector element 65 during this motion.

If the detector engages an empty bobbin as indicated in Fig. 5 as the lay advances the teeth of the tip 67 will slide to the right along the bobbin to the dotted line position indicated in Fig. 5. During this movement the spring 75 tends to urge the arm 69 rearwardly and the latter turns around a corner or shoulder 85 of the lug 50 as a pivot until the extreme left end of the arm 69 engages the screw 80 as indicated in dotted lines in Fig. 5. Movement of the parts from the full to the dotted line position in Fig. 5 may be considered as the initial stage of indication, upon completion of which electric contact is established between the arm 69 and the screw 80. As the lay continues to advance the fulcrum for arm 69 shifts from the shoulder 85 to the screw 80 and the detector finger 65 undergoes a further angular movement to the right. Movement of the parts from the dotted line position of Fig. 5 to the position shown in Fig. 6 and back again to the dotted line position shown in Fig. 5 as the lay reciprocates may be considered as the second stage of the detecting operation during which screw 80 serves as the fulcrum for the detector 65. The hole 78 is sufficiently large to permit the angular motions indicated in Figs. 5 and 6.

The right hand side of the lug 50 is provided with a wall 86 which engages the left side of the forward part of the rod 66 and cooperates with the rod 60 and spring 75 to hold the detector in the normal position shown in full lines in Fig. 5. The short forward lateral extension 72 of the carrier 68 is preferably of such length that it does not engage the rod 60 during any part of the detecting operation, otherwise the detector

would slide forwardly along the rod and cause the arm 69 to break contact with the screw 80.

The path of the grounded part of the circuit through the detector may take several courses. Thus, the weight of the rear part of the detector element will be such as to exert an upward force on the short lateral extension 72 causing the latter to engage the rib 36 thereover. The ground may also be established between the arm 69, the rod 60 and the top shell 25 at the point where the forward end of rod 60 enters notch 62. A third path and the one on which I chiefly rely is through the spring 75. The rear part of the spring is pushed against the arm 69 to have good electrical contact therewith, while the forward part of the spring 75 engages the peripheral wall 40 of the top metal shell. In order to insure contact between the spring and the wall 41 the latter is widened as at 87 where it contacts with the front end 77 of the spring. When the detector completes the first stage of its detecting movement the rear part of the spring 75 will in all likelihood be moved against the rod 60 so that the spring and the rod establish parallel grounded paths.

The screw 80 is made adjustable so that it can be moved toward and from the arm 69 to shorten or lengthen the first stage of the detecting operation. If it is found for instance that any particular detector made according to my present invention is subject to vibration in a direction from the full line toward the dotted line position in Fig. 5, the screw 80 may be moved rearwardly so as to avoid undesirable contact with the arm 69 due to such vibration.

The rear part 76 of the spring normally lies along that part of the arm 69 adjacent to the rod 60 when the parts are in the full line position shown in Fig. 5. Because of the angular movement of the detector arm the point of contact between the spring and the latter arm 69 will move to the right as the detector finger moves angularly, thereby applying pressure to the arm along a series of points which move progressively away from the screw 80. The spring therefore becomes increasingly effective to maintain good contact between the arm 69 and the screw 80 during the second stage of the detecting operation.

In order to prevent binding of the spring 75 the latter is formed with a hole 88 slightly larger than rod 60, see Fig. 3, and a small pin 89 on arm 69 limits movement of the spring end 76 to the right as viewed for instance in Fig. 6.

From the foregoing it will be seen that I have provided a simple form of side slipping electrically indicating weft detector comprising a casing formed of a pair of shell members held together normally in fixed angular position by the screw 38 and the interengaging parts of the peripheral walls and tongue 41 and lug 50. It will further be seen that the detector moves through two stages when giving a complete indication, the first stage being completed when contact is established between the lateral arm 69 and the screw 80 and the second stage continuing thereafter during which contact is established. It will also be noted that the spring acts by angular movement of the arm 69 to apply its force at progressively increasing distances from the screw 80 as the detector 65 completes its angular movement to the right during the second stage, thereby insuring good contact. It will also be seen that multiple paths are provided through the detector between the top metallic shell thereof and

the screw 80. Furthermore, the rod 60 serves as a guide for the detector and spring as well as providing one of the grounded paths through the detector. Also, the carrier 68 has front and back 5 arms which cooperate with the ribs in contact with them to maintain the detector tip in normal detecting position, and this relationship results in contact between the short forward lateral arm 72 and the metallic rib thereover to provide another grounded path to the detector. Furthermore, the pivot around which arm 69 turns shifts from corner or shoulder 85 to screw 80 at the end of the first stage of indication.

Having thus described my invention it will be seen that changes and modifications may be made therein by those skilled in the art without departing from the spirit and scope of the invention and I do not wish to be limited to the details herein disclosed, but what I claim is:

1. In a side slipping electrically indicating weft detector having a body, guide means extending backwardly and forwardly on the body, a weft detector member mounted for sliding and angular movement on said body, a lateral arm on the detector member slidable along and movable angularly relatively to said guide means, a stop on the body for the lateral arm, a spring mounted on the body engaging the lateral arm and normally holding the latter against the stop to locate the detector member in normal position, and an electric contact insulated from the body and normally out of contact with said arm, said detector member when moving angularly relatively to the body causing said arm to move along and angularly relatively to said guide means and into engagement with said electric contact.

2. In a side slipping electrically indicating weft detector having a body, guide means extending backwardly and forwardly on the body, a weft detector member mounted for sliding and angular movement on said body, a laterally extending arm on said member slidable along and movable angularly with respect to the guide means and extending on opposite sides of said guide means, a stop on the body engaging said arm on opposite sides of the guide means, a spring on said body normally holding the arm against said stop to locate said detector member in normal position, and an electric contact insulated from said body and normally spaced from said arm, the latter when moving angularly with respect to the guide means engaging said electric contact.

3. In a side slipping electrically indicating weft detector having a body, a backwardly and forwardly extending guide rod mounted on the body, a block of insulating material on said body extending on opposite sides of said guide rod, a weft detector member mounted for sliding and angular movement on said body and having a lateral arm extending along said opposite sides of said guide rod, the latter extending through the arm and the latter being slidable along and movable angularly with respect to the guide rod, spring means mounted on the body engaging said arm and holding the latter against said opposite sides of said block to locate the detector member in normal position, and an electric contact carried by said block and normally spaced from said arm, the latter when sliding along and moving angularly relatively to said guide rod moving into engagement with said electric contact.

4. In a side slipping electrically indicating weft detector having a body, a block of insulating material on said body, an electric contact carried by said block, a guide rod extending backwardly

and forwardly on the body and having the rear end thereof supported by said block, a weft detector member mounted for sliding and angular movement on the body and having an arm surrounding the guide rod and slideable therealong and movable angularly relatively to said guide rod and said block, and spring means engaging the arm and normally holding the latter against said block to locate said detector member in normal position with the arm out of engagement with said electric contact, said detector member when moving angularly relatively to said body against the action of said spring means causing said arm to slide along said guide rod and move angularly relatively to the block and into engagement with the electric contact.

5. In a weft detector having a body, a side slipping weft detector member mounted on said body for sliding and angular movement relatively thereto, a lateral arm projecting from said detector member, a stop carried by said body, spring means holding said arm against said stop to locate the detector member in normal position, and an electric contact carried by and insulated from said body, said detector member moving angularly through two stages when indicating weft exhaustion and during the first stage moving about a point of contact between said stop and said arm to cause engagement between said arm and said contact and in the second stage moving about a point of engagement between said arm and said electric contact.

6. In a weft detector having a body, a side slipping weft detector member mounted on the body for sliding and angular movement relatively thereto, a stop on said body, an electric contact supported by and insulated from the body, an arm forming part of said detector member, and resilient means holding said arm against said stop and out of engagement with said electric contact, said detector member when indicating weft exhaustion moving angularly through a first stage about a point of contact between said arm and said stop to cause said arm to move into engagement with the electric contact and said member thereafter moving through a second angular stage about a point of engagement between said arm and said electric contact.

7. In a weft detector having a body, a weft detector member movable slideably and angularly with respect to the body, an electric contact insulated from the body, a lateral arm forming part of the detector member, a stop for the arm, a spring mounted on the body and normally holding said arm against the stop to locate the detector member in normal position, and a stationary guide rod extending backwardly and forwardly on the body and passing through said spring and arm and supported by said stop, said detector member when indicating weft exhaustion having a first stage of angular movement against the action of said spring around a point of contact between said arm and said stop as the arm moves relatively to said guide rod to cause engagement between the arm and electric contact, and said detector member having a second stage of angular movement about a point of engagement between said arm and said electric contact as said arm continues to move relatively to said guide rod.

8. In a weft detector having a body, a weft detector member mounted on said body for sliding and angular movement relatively thereto, said member having a rearwardly extending part supporting a bobbin feeler tip and having a forward

extension, a lateral arm on said member intermediate said forward extension and said tip, a stop on the body for said arm, resilient means engaging said arm and holding the latter against said stop to locate said tip and forward extension in normal position, and an electric contact carried by but insulated from said body and normally out of engagement with said arm, said detector member when moving angularly relatively to the body causing said arm to engage the electric contact, said forward extension cooperating with said body to maintain said tip in detecting position against the action of gravity.

9. In a weft detector having a case formed with top and bottom spaced horizontal walls, a weft detector element slidably and angularly movable on said body, an arm on said member located between said top and bottom walls and having a forward extension between said walls, an electric contact supported by but insulated from said body and normally out of contact with said arm, said detector member when moving angularly relatively to the body causing engagement between said arm and electric contact and said forward extension engaging the upper wall to support the rear part of the detector against the action of gravity.

10. In a weft detector having a body provided with spaced top and bottom horizontal walls, a stop having a vertical surface fixed with respect to said body, a weft detector member having a rearwardly extending portion provided with a bobbin feeler tip and having a laterally extending arm and a forward extension in front of said arm, said arm and extension being between said walls, an electric contact carried by but insulated from said body, and a spring carried by said body normally engaging the arm and holding the latter against said vertical surface to maintain said bobbin tip in detecting position against the action of gravity prior to a detecting operation, said detector member during a detecting operation causing the arm to move away from said vertical wall and into engagement with said electric contact, and said forward extension engaging the upper wall to support the rear portion of the detector member and hold said tip in detecting position against the action of gravity while said arm is out of engagement with said vertical surface.

11. In a side slipping electrically indicating weft detector having a casing formed of top and bottom members, a depending vertical wall on the top member, an ascending wall on the bottom member abutting the depending wall, a block of insulating material fixed with respect to the bottom member and projecting above said ascending wall, means to secure said members together, parts of said depending wall engaging said block, the latter and said parts of the depending wall cooperating with said means to hold said members in fixed relative angular position, an electric contact carried by said block of insulating material, and weft detector means extending into said casing and having a part held against said block of insulating material spaced from said electric contact but movable angularly upon indication of weft exhaustion into engagement with said electric contact.

12. In a side slipping electrically indicating weft detector having a casing formed of top and bottom members, a depending wall formed on said top member, an ascending wall on the bottom member abutting the depending wall, a stop fixed with respect to the bottom member and ex-

tending along the rear edge thereof, an electric contact carried by said stop and insulated from said bottom member, means to hold said members together, parts of said depending wall engaging said stop and cooperating with said means to prevent angular movement of the members relatively to each other, and a weft detector extending between said members and having a part held against said stop and positioned for engagement with said electric contact when the detector slips laterally relatively to said casing.

13. In a side slipping electrically indicating weft detector having a casing formed of top and bottom members, a depending wall formed on the top member, an ascending wall formed on the lower member and abutting the depending wall, a stop along the rear edge of one of said members projecting vertically beyond the wall of said one member into engagement with the wall of the other member, means to secure said members together, said means and stop and said other wall cooperating to prevent relative angular movement of said members, an electric contact carried by said stop and insulated therefrom, and a weft detector extending between said members and having a part movable into engagement with said electric contact when said element slips laterally relatively to said casing.

14. In a side slipping electrically indicating weft detector having a casing formed of top and bottom members, a depending wall on the top member, an ascending wall on the lower member abutting the depending wall, a block along the rear edge of the bottom member, said bottom member and ascending wall and block being integral and formed of electric non-conducting material, an electric contact supported by said block, and a weft detector having a lateral arm within said casing normally held against said block and spaced from said electric contact, said element when slipping laterally with respect to the casing effecting movement of said lateral arm into engagement with said electric contact, the upper member being formed of electric conducting material and having provision for attachment to a grounded support.

15. In a side slipping electrically indicating weft detector having a casing formed of top and bottom members, a depending wall on the top member, an ascending wall on the bottom member 50

abutting the depending wall, said walls and members forming a hollow cavity in the casing, an electric contact supported by and insulated with respect to one of said members, a stop formed at the rear part of one of said members, a weft detector having a tip at the rear end thereof and extending into said cavity, a lateral arm on said detector element located within the cavity, a curved leaf spring located within the cavity and normally holding said lateral arm against said stop to position the weft detector and lateral arm in normal position with the lateral arm out of engagement with said electric contact, and means extending forwardly from said lateral arm and fixed with respect to the detector element and located within said cavity to engage the upper member and assist in supporting the weft detector against downward movement under the action of gravity, said detector slipping laterally when indicating weft exhaustion and moving said lateral arm into engagement with said electric contact.

16. A weft detector element for a weft detector having top and bottom members and a stop on one of said members, said detector having also a guide rod, said element comprising a rearwardly extending part provided with a bobbin feeler tip, a lateral arm to extend along the stop and having an opening therein to receive said guide rod, and a forward extension on said detector element for location between said top and bottom members to cooperate with the top member and support said bobbin tip against the action of gravity.

17. In a side slipping electric indicating weft detector having a body provided with a stop and having an electric contact supported by but insulated from the body, a weft detector element having a rearwardly extending arm provided with a bobbin feeler tip, a lateral arm extending from the detector element toward the electric contact and movable angularly toward said electric contact, and a curved leaf spring bearing against said arm and holding the latter against said stop out of engagement with the electric contact, said spring being so shaped that as the lateral arm moves angularly toward said electric contact during a side slipping movement of the detector element the point of engagement between the spring and said lateral arm moves progressively away from said electric contact.

RICHARD G. TURNER.
